TOY TRAIN CAR

Kenneth Van Dyck, Westport, Conn., assignor to The Lionel Corporation, New York, N.Y., a corporation of New York

Application January 29, 1959, Serial No. 54,370

Term of patent 14 years

(Cl. D34—15)

Fig. 1 is a front view of a toy train car in accordance with my design;

Fig. 2 is a top plan view of Fig. 1;

Fig. 3 is a left end view of Fig. 1; and

Fig. 4 is a right end view of Fig. 1.

The side of the car (not shown) in the figures is substantially identical to the side shown in Fig. 1.

I claim:

The ornamental design for a toy train car, as shown and described.
